(57) **CLAIM**

The ornamental design for an electric power measuring device as shown and described.

DESCRIPTION

1. Electric power measuring device

1.1 : Front perspective

1.2 : Back perspective

1.3 : Front

1.4 : Back

1.5 : Left

1.6 : Right

1.7 : Top

1.8 : Bottom

The broken lines disclose portions of the electrical power measuring device that form no part of the claimed design.
